UNITED STATES PATENT OFFICE.

WILLIAM L. SÜTTERLIN AND EDWARD E. SCHILLING, OF TRENTON, NEW JERSEY.

DESIGN FOR A TRACE-GUARD.

SPECIFICATION forming part of Design No. 27,718, dated October 12, 1897.

Application filed August 14, 1897. Serial No. 648,328. Term of patent 3½ years.

To all whom it may concern:

Be it known that we, WILLIAM L. SÜTTERLIN and EDWARD E. SCHILLING, citizens of the United States, residing at Trenton, in the county of Mercer and State of New Jersey, have invented and produced a new and original Design for Trace-Guards, of which the following is a specification, reference being had to the accompanying drawings, showing a part thereof.

This invention relates to new and useful designs for trace-guards; and it consists of a trace-guard having a pleasing configuration or outline of a specific nature, which will be more fully hereinafter described and claimed.

In the accompanying drawings, Figure 1 is a perspective view of a trace-guard embodying the improved design. Fig. 2 is a section on the line X X of Fig. 1.

Referring to the drawings, wherein similar numerals of reference are employed to indicate corresponding parts in the views, the numeral 1 designates an elliptical-shaped head having an opening 2 therein, whose walls in the main partake of the same outline as the head, but having in addition sloping sides 3, connected by a straight wall 4. From the head 1 the opposite edges of the guard are formed with curved projections 5, continuing in the longer curved enlargements 6, the latter at their outer ends converging and ter-

minating in curved recesses 7, forming the inner walls of outer-curved oppositely-extending arms 8, which have a depression 9 between the same.

In the body of the carrier, on opposite sides, are a series of substantially pear-shaped openings 10 and 11, which diminish in size and arranged in regular lines with each other, converging slightly toward the outer end of the guard. The outer surface of the guard is slightly rounded and the inner surface formed with tapered corrugations 12. The said outer surface of the guard may be suitably plated or colored, as may be desired, to present a pleasing appearance, and when the entire device is completed in the manner stated it produces a very ornamental form of guard.

Having thus described the invention, what is claimed as new is—

The design for trace-guards herein shown and described.

In testimony whereof we have signed this specification in the presence of two subscribing witnesses.

WILLIAM L. SÜTTERLIN.
EDWARD E. SCHILLING.
